UNITED STATES PATENT OFFICE.

CLARENCE E. HAYNES, OF GENESEE, IDAHO.

PUZZLE.

SPECIFICATION forming part of Letters Patent No. 736,251, dated August 11, 1903.

Application filed March 4, 1903. Serial No. 146,128. (No model.)

To all whom it may concern:

Be it known that I, CLARENCE E. HAYNES, a citizen of the United States, residing at Gene-
see, in the county of Latah and State of Idaho,
5 have invented new and useful Improvements
in Puzzles, of which the following is a speci-
fication.

This invention relates to puzzles; and the primary object thereof is to provide a game, 10 or puzzle requiring considerable skill in its manipulation, and thus afford amusement to the person or persons operating it.

The invention consists in a box or case divided into a plurality of compartments, one 15 of which is the main compartment and the others being secondary compartments parallel with each other and divided by a central alley, the compartments having alternating and communicating openings normally closed 20 by a suitable cut-off.

The invention further consists in providing means for manipulating the cut-off so that communication may be had through the openings with the various compartments.

25 The invention further consists in providing varying enlarged game-pieces or spheres, each sphere or game-piece being designated for a particular compartment.

The peculiar manner of accomplishing the 30 desired result will be specifically described hereinafter and illustrated in the accompanying drawings, in which—

Figure 1 is a top plan view of a puzzle constructed in accordance with my invention. 35 Fig. 2 is a vertical longitudinal section therethrough. Fig. 3 is a transverse sectional view on the line 3 3 of Fig. 1. Fig. 4 is a transverse sectional view on the line 4 4, Fig. 1; and Fig. 5 is a detail view of the cut-off 40 and its operating-rod.

The reference-numeral 1 designates an approximately rectangular box or case provided with a suitable transparent cover 2, which preferably consists of glass. One end of the 45 box or case is divided into a compartment 3 by a vertical transverse partition 4, which extends entirely across the case. Intermediate the ends of the partition 4 and preferably at the middle thereof an opening 5 is formed, 50 which is arched, and on the respective sides of the opening vertically longitudinally-extending partitions or walls 6 and 7 are arranged

in the case, one end of each partition abutting against the partition 4 and the other end being secured to the end of the box. These 55 parallel partitions or walls form a longitudinal alley or raceway 8, alining with the opening 5 in the partition 4. Between the ends of the partitions 6 and 7 are transverse partitions 8' and 9, parallel with the partition 4 60 and dividing the box into compartments or pockets 10, 11, 12, and 13. The pockets or compartments 10 and 11 are provided on one side of the alley, while those designated by the reference-numerals 12 and 13 are on the 65 opposite side. The openings 14 in the partitions 6 and 7 alternate with each other and are provided for the purpose of permitting communication between the alley and the several compartments or pockets and between 70 one pocket and the remaining ones.

In the alley formed by the partitions 6 and 7 is a longitudinally-sliding cut-off, which comprises two side bars 15 and 16, connected by transverse bars 18 and 19, and an operating-rod 20, which extends from the bars through the partition 4 and through one end of the case 1. A coiled spring 21 bears against a washer 22 on the rod 20 and at the other end against the partition 4. The convolutes 80 of this spring 21 surround the rod, and as the expansive force of the spring is exerted against the bar 18 the cut-off will be normally forced against the rear end of the case. The oppositely-arranged bars 15 and 16 have 85 openings 23 formed therein, which are normally out of alinement with the openings 14, but which can be brought into alinement therewith by pulling upon the rod 20. Of course the openings 23 in the respective side 90 bars must alternate, so that when the cut-off is slid against the springs the openings in the bars and partitions will register.

Each pocket or compartment is provided with a supplementary game-piece, it being 95 the object of the game to cause each game-piece to be transferred from the main compartment 3 to the particular compartment for which it is intended—for instance, there being four compartments, game-pieces or 100 spheres of as many different colors will be placed in the compartment 3. These game-pieces are designated by the reference-numeral 24 and are preferably circular. Hav-

ing properly assembled the game-pieces in the main compartment they will be manipulated so as to pass through the arched opening 5 into the cylindrical alley. All of the 5 game-pieces of one designation or color must be caused to enter the pocket or compartment 10, those of another color are to be placed in the compartment 11, and the remaining ones in the compartments 12 and 13, as previously 10 arranged. Considerable difficulty will be experienced in properly manipulating the box, because when the cut-off is retracted against the spring all of the openings 23 register with a corresponding opening 14, and while 15 it will be comparatively easy to have the game-pieces enter any one of the compartments it will be a difficult matter to retain the proper ones in their pockets while causing the remaining ones in the alley to pass 20 through the proper openings.

The floors of the several compartments can be suitably ornamented, as can also the game-pieces, and suitable rules may be made for playing the game by one or more persons. I 25 therefore do not limit myself to the exact details of construction shown and described, but I reserve the right to make such changes and alterations as would properly come within the scope of the appended claims.

30 Having thus described the invention, what is claimed as new is—

1. In a device of the character described, the combination of a case having a main com-

partment at one end extending transversely thereacross, longitudinally-disposed secondary compartments between the said main compartment and the opposite end of the case, the said secondary compartments having a longitudinally-disposed raceway between the same, all of the compartments having communicating openings leading to the raceway, and a longitudinally-slidable cut-off means disposed in the raceway. 35

2. In a device of the character described, the combination of a case divided into a plurality of compartments, the several compartments being provided with alternating openings, and a spring-pressed sliding cut-off for normally closing the openings. 45

3. In a device of the character described, the combination of a transverse partition having an opening, parallel partitions extending longitudinally of the device and arranged on each side of the opening in the first-named partition, the last-named partition being 50 formed with openings, and a spring-pressed cut-off interposed between the parallel partitions for normally closing the openings in the parallel partitions.

In testimony whereof I affix my signature 55 in presence of two witnesses.

CLARENCE E. HAYNES.
